United States Patent Office

Des. 183,153
Patented July 1, 1958

183,153

AUTOMOBILE

Karl. Wilfert, Stuttgart-Degerloch, Germany, assignor to
Daimler-Benz Aktiengesellschaft, Stuttgart-Unterturk-
heim, Germany

Application May 4, 1956, Serial No. 41,357

Claims priority, application Germany November 14, 1955

Term of patent 7 years

(Cl. D14—3)

Figure 1 is a front view of an automobile, embodying my new design;

Figure 2 is a partial side view;

Figure 3 is a partial plan view; and

Figure 4 is a perspective view of the automobile with the features of the invention shown in full lines.

The dominant features of my design are shown in full lines in Figures 1 through 4, while the remaining parts of the automobile are of conventional construction.

I claim:

The ornamental design for an automobile, substantially as shown and described.
